UNITED STATES PATENT OFFICE.

CHARLES ALGERNON PARSONS, OF NEWCASTLE-UPON-TYNE, ENGLAND.

GEARED-TURBINE INSTALLATION FOR SHIP PROPULSION.

1,302,962.

Specification of Letters Patent.

Patented May 6, 1919.

Application filed October 23, 1916, Serial No. 127,304.

To all whom it may concern:

Be it known that I, CHARLES ALGERNON PARSONS, a subject of the King of Great Britain and Ireland, residing at Heaton Works, Newcastle-upon-Tyne, in the county of Northumberland, England, have invented 5 certain new and useful Improvements in and Relating to Geared-Turbine Installations for Ship Propulsion, of which the following is 10 a specification.

The present invention relates to a marine propulsion system of differently speeded turbines driving a common shaft in which two or more turbines are geared to the propeller shaft through double reduction gearing, such, for example, as are described in 15 the British patent specification No. 25651 of 1909.

It is well known that the reaction type of 20 blading is in itself more efficient than any other type, but its high efficiency is in practice to a certain extent encroached upon by reason of the losses which occur through the packing of the balancing piston and through 25 the clearance spaces of the tips of the blades, these losses being most serious in the high pressure stages.

The first mentioned loss may be obviated 30 by constructing the turbine in the manner described in the British specification No. 953 of 1913 in which the balancing pistons are dispensed with and the axial thrust upon the rotor is taken by a pivoted thrust bearing.

The second mentioned loss may be considerably reduced by fitting projecting shrouds 35 to the blades and controlling the clearance of axial adjustment as described in the British patent specification No. 12347 of 1901 and this loss can be further reduced by making 40 the turbine of small diameter with long blades, the reduction in diameter being accompanied by a corresponding increase in the rate of revolution so as to maintain a 45 high blade velocity corresponding to maximum efficiency.

In order to obtain the maximum blade height practically possible for each stage, all 50 the stages may be sub-divided into separate units with separate pinions corresponding to different speeds, and proposals have been made for installations of the type to which this invention relates, in which a large 55 number of geared turbines are employed, as is the case in the British patent specification No. 25651 of 1909. The gain so obtained,

however, is not sufficient to warrant the subdivision and the cost and weight of such installations is extremely high.

The object of the present invention is to 60 provide an installation of the type indicated in which very high efficiencies can be obtained with a minimum cost and weight.

The invention consists in a geared turbine 65 installation for ship propulsion of the type indicated comprising three turbines connected in series for steam flow and operating the propeller shaft through double reduction gearing, all the turbines being provided with blading of the reaction type and being constructed without balancing pistons, the high 70 and intermediate pressure turbine pinions being arranged to operate a common gear wheel, while the low pressure turbine pinion operates another gear wheel, each of these 75 gear wheels operating separate co-axial pinions engaging with a main gear wheel mounted on the propeller shaft, the high pressure turbine having the highest rate of revolution and the low pressure turbine having the lowest rate of revolution, while the high and intermediate pressure turbines each develop substantially one quarter of the 80 total power.

The invention further consists in such an 85 installation in which the high pressure turbine and preferably also the intermediate pressure turbine, are provided with end-tightening shrouds of the type described in the British patent specification No. 12347 of 90 1901.

The invention also consists in an installation as above described in which the high pressure turbine is specially designed to withstand the high temperatures resulting 95 from the employment of superheated steam.

Referring to the accompanying drawings:

Figure 1 is an end view of an installation 100 according to the invention, while

Fig. 2 is a plan of the same.

In the installation illustrated the high pressure turbine *a* and the intermediate turbine *b* drive pinions which are geared to a common gear wheel in the casing *c* driving 105 the pinions *d*. The low pressure turbine *e* drives a gear wheel in the casing *f* on the shaft carrying the pinion *g*. The pinions *d* and *g* drive the common gear wheel *h* mounted on the propeller shaft. The steam 110 flow is through the turbines *a*, *b* and *e* in series. The turbines *a*, *b* and *e* are fitted with

blading of the reaction type and balancing pistons are dispensed with, the axial thrust upon the rotor being taken by a pivotal thrust bearing. The blades are fitted with 5 projecting shrouds and the clearance is controlled by an axial adjustment as described in the British patent specification No. 12347 of 1901. Each of the turbines *a* and *b* provide substantially a quarter of the power 10 while the turbine *e* provides one-half the power.

In the section of the turbine shown in Fig. 2 the blades 1 of the rotor are provided with entightening shrouds 2 and the blades 15 3 of the stator with entightening shrouds 4.

Considerable advantage is obtained by an installation such as above described. Owing to the high rate of revolution of the turbines obtained by the use of double reduction 20 gearing, the turbines are of small diameter and length, and the weight and cost are therefore small. Consequently the blade clearance losses and the rotor thrust to be carried are also small.

25 The closest approximation to the maximum practically possible blade height relative to the diameter of the turbine is obtained throughout all the stages, while only a small number of separate units is employed.

In cases in which superheated steam is employed the superheat is confined to the high pressure turbine *a* which on account of its small dimensions would have a simple and 35 compact casing not liable to distortion, while the differential expansions which take

place at the high temperatures would be so small as not to effect the endwise control of the clearances by the adjusting block.

Having now fully described and ascer- 40 tained my said invention, and the manner in which it is to be performed, I declare that what I claim is:—

A geared turbine installation for ship 45 propulsion, comprising in combination three turbines including a high pressure turbine, an intermediate pressure turbine and a low pressure turbine, means for connecting said turbines in series as regards steam flow, pinions on the shaft of each of said turbines, 50 two intermediate shafts, gear wheels on said intermediate shafts, the pinions on the high pressure and intermediate pressure turbine shafts engaging with one of said gear wheels and the pinion on the low pressure turbine 55 shaft engaging with the other of said gear wheels, pinions on said intermediate shafts, gear wheels on the propeller shaft, said intermediate shaft pinions engaging with said propeller shaft gear wheels, the pinion on 60 said high pressure turbine shaft being of smaller diameter than the pinion on said intermediate turbine shaft and the pinion on said intermediate pressure turbine shaft being smaller than the pinion on said low pressure turbine shaft, said high pressure turbine and said intermediate pressure turbine each developing substantially one quarter 65 of the total power, as set forth.

In testimony whereof, I have affixed my 70 signature.

CHARLES ALGERNON PARSONS.
